[54] COMBINED CARD FILE AND CURVED TOP CARDS

[75] Inventors: Hildaur L. Neilsen, Metuchen; Martin Glaubinger, Teaneck, both of N.J.[73] Assignee: Rolodex Corporation, Secaucus, N.J.[] Term: 14 Years[21] Appl. No.: 783,860[22] Filed: Apr. 1, 1977*Related U.S. Application Data

[63] Continuation of Ser. No. 561,778, Mar. 25, 1975, Pat. No. Des. 247,042.

[51] Int. Cl. .... D19—02[52] U.S. Cl. .... D19/76[58] Field of Search D19/75, 76, 84, 65, D19/22, 95; 40/68.6; 206/425; D9/234

[56]

References CitedU.S. PATENT DOCUMENTS

D. 204,217	3/1966	Sims	D19/76
D. 205,869	9/1966	Hahn	D9/234
D. 216,346	12/1969	Rhoades	D19/84
2,472,567	6/1949	Bruen	D19/76

Primary Examiner—George P. Word*Attorney, Agent, or Firm*—Robert E. Burns; Emmanuel J. Lobato; Bruce L. Adams[57] CLAIM

The ornamental design for a combined card file and curved top cards, as shown and described.

DESCRIPTION

FIG. 1 is a side elevational view of a combined card file and curved top cards showing our new design,

FIG. 2 is a top plan view,

FIG. 3 is a front elevational view,

FIG. 4 is a rear elevational view, and

FIG. 5 is a bottom plan view.

FIG. 1

FIG. 2

FIG. 3

FIG. 4FIG. 5